UNITED STATES PATENT OFFICE.

HERMAN J. FREDERICK, OF PITTSBURGH, PENNSYLVANIA.

WRINGER.

1,016,685.

Specification of Letters Patent. Patented Feb. 6, 1912.

Application filed March 26, 1911. Serial No. 615,718.

To all whom it may concern:

Be it known that I, HERMAN J. FREDERICK, a citizen of the United States of America, residing at Pittsburgh, in the county of Allegheny and State of Pennsylvania, have invented certain new and useful Improvements in Wringers, of which the following is a specification, reference being had therein to the accompanying drawing.

10 This invention relates to wringers especially designed for wringing towels over the wash basins of tonsorial parlors, thereby preventing the hands of a barber from being injured, especially when subjected to extremely hot water.

15 The primary object of my invention is to provide a wringer that can be easily attached to a wash basin, sink or other support and quickly operated to thoroughly 20 wring a towel or other piece of fabric whereby it can be handled and immediately used.

25 Another object of the invention is to furnish a wringer with a support for a towel or piece of fabric, the support being arranged whereby the towel will be normally held in position to be easily obtained by a barber without wetting the hands.

30 A further object of the invention is to provide a wringer with a novel sprinkling device and with yieldable wringing rollers that prevent a towel or piece of fabric from being injured during the wringing operation.

35 A still further object of the invention is to accomplish the above results by a mechanical construction that is simple, durable and highly efficient for the purposes for which it is intended.

40 With the above and other objects in view, the invention resides in the novel construction, combination and arrangement of parts to be hereinafter specifically described and then claimed.

45 Reference will now be had to the drawings, wherein like numerals of reference designate corresponding parts throughout the several views, in which:

50 Figure 1 is a plan of the wringer, Fig. 2 is a vertical longitudinal sectional view of the same, Fig. 3 is a side elevation of the wringer, and Fig. 4 is a vertical cross sectional view of the same.

55 A wringer in accordance with this invention comprises a horizontal support 1 having end walls 2 and 3, a rear curved wall 4,

and a curved deflector plate 5 connecting the end walls 2 and 3. The support 1 is provided with depending L-shaped clamping members 6 and the ends of said members have clamping screws 7, whereby the support 1 can be secured to the edge of a basin or other support.

Journalized in the end walls 2 and 3 are longitudinal shafts 8 and 9, and mounted upon the ends of said shafts at the outer sides of the end walls 2 and 3 are bearings 10 and 11 respectively having the lower ends thereof provided with sector gears 12 and 13, said gears meshing whereby they can be moved in unison. The bearings 10 support the pintles 14 of a roller 15, said roller having a cover of corrugated rubber or other yieldable material 16. The pindle at one end of the roller is provided with a gear wheel 17 meshing with a gear wheel 18 revolvably supported by the bearing 10 adjacent to the end wall 3. The gear wheel 18 meshes with a gear wheel 19 loosely mounted upon the shaft 8 protruding from the end wall 3, and this gear wheel is provided with a crank 20 whereby a rotary movement can be imparted to the roller 15.

The bearings 11 have housings 21 for spring pressed bushings 22 supporting the pintles 23 of a roller 24 constructed similar to the roller 15. The bushings 22 are spring pressed by coiled compression springs 25 arranged in the housings 21, these springs allowing the roller 24 to yield when in operation.

26 The end wall 3 is provided with a stud 26 and movably mounted upon said stud is the inner end of a lever 27 having a sector gear 28 meshing with the sector gear 12 of the bearing 10. The lever 27 has a tooth 29 adapted to engage a rack 30, carried by the outer side of the end wall 3, whereby said lever can be locked in an adjusted position. This lever is employed for swinging the rollers 15 and 24 away and toward each other for a purpose that will presently appear.

27 Mounted upon the upper edges of the end walls 2 and 3 is a longitudinal support 31 adapted to support a towel or piece of fabric with the ends of the towel or piece of fabric in the basin to which the support 1 is connected.

28 Detachably connected to the upper edge of the curved deflector 5 by a set screw 32 is a bracket 33 and movably connected to the

upper end of the bracket 33 is a pivoted head 34 having a hot water connection 35 and a cold water connection 36. These connections are in communication with a pipe 37, carried by said head, and the end of the pipe supports a longitudinal tubular sprinkler or distributing head 38.

With the rollers 15 and 24 swung apart, a towel or other piece of fabric can be easily suspended in a basin over the support 31, and then by adjusting the lever 27, the rollers 15 and 24 can be swung into engagement with the towel held by the support 31. By operating the crank 20, a rotary movement can be imparted to the roller 15 and the towel gradually elevated and thoroughly wrung; the roller 24 revolving by frictionally engaging said towel. The towel is prevented from being injured as the roller 24 can recede when any irregular surfaces are encountered in the towel as it passes between the rollers.

Prior to elevating the towel between the rollers 15 and 24, the sprinkler 38 is swung upwardly, thus allowing a barber to grip the towel as it is fed upwardly between the rollers without getting the hands wet. After the towel has been removed, the rollers 15 and 24 can be supported to permit of another towel being placed upon the support 31. The sprinkler 38 can then be swung into position and hot or cold water precipitated upon the towel to thoroughly rinse the same. The deflector plate 5 deflects water wrung from the towel into the basin to which the wringer is attached.

The wringer in its entirety can be made of light and durable metal and finished to present a neat appearance.

40 What I claim is:—

1. A wringer comprising end walls, longitudinal shafts journaled in said walls, bearings supported by said shafts and adapted to be shifted in unison, rollers revolvably mounted in said bearings, and a towel support connecting said end walls and adapted to support a towel between said rollers.

2. A wringer comprising end walls, longitudinal shafts journaled in said walls, bearings supported by said shafts and adapted to be shifted in unison, rollers revolvably mounted in said bearings, a towel support connecting said end walls and adapted to support a towel between said rollers, means carried by one of said bearings and adapted to revolve the roller thereof, means carried by one of said end walls and adapted to shift said bearings in unison, and a sprinkler adjustably supported above said rollers.

60 3. A wringer comprising a support including a pair of end walls and a deflector connecting said walls at the rear thereof, longitudinal shafts journaled in and projecting from said end walls, two pairs of shiftable bearings mounted upon the pro-

jecting ends of said shaft and adapted to be moved in unison, said bearings projecting above the end walls, a roller revolvably supported by each pair of bearings above the end walls, means carried by one of the bearings of one pair for revolving the roller carried by said pair, means carried by the bearings of the other pair for forcing the roller carried thereby into yielding engagement with the other roller, and a support connecting said end walls at the top thereof and adapted to extend up between said rollers for supporting a towel.

4. A wringer comprising a support including a pair of end walls and a deflector connecting said walls at the rear thereof, longitudinal shafts journaled in and projecting from said end walls, two pairs of shiftable bearings mounted upon the projecting ends of said shaft and adapted to be moved in unison, said bearings projecting above the end walls, a roller revolvably supported by each pair of bearings above the end walls, means carried by one of the bearings of one pair for revolving the roller carried by said pair, means carried by the bearings of the other pair for forcing the roller carried thereby into yielding engagement with the other roller, a support connecting said end walls at the top thereof and adapted to extend up between said rollers for supporting a towel, each of said bearings having its lower portion provided with teeth, the teeth of one bearing meshing with the teeth of the other bearing, and means carried by one of said end walls and provided with teeth adapted to engage in the teeth of one of said bearings, said means when shifted in one direction moving said rollers away from each other and when shifted in the other direction moving said rollers toward each other.

5. A wringer comprising a support including a pair of end walls and a deflector connecting said walls at the rear thereof, longitudinal shafts journaled in and projecting from said end walls, two pairs of shiftable bearings mounted upon the projecting ends of said shaft and adapted to be moved in unison, said bearings projecting above the end walls, a roller revolvably supported by each pair of bearings above the end walls, means carried by one of the bearings of one pair for revolving the roller carried by said pair, means carried by the bearings of the other pair for forcing the roller carried thereby into yielding engagement with the other roller, a support connecting said end walls at the top thereof and adapted to extend up between said rollers for supporting a towel, each of said bearings having its lower portion provided with teeth, the teeth of one bearing meshing with the teeth of the other bearing, means carried by one of said end walls and provided with

teeth adapted to engage in the teeth of one of said bearings, said means when shifted in one direction moving said rollers away from each other and when shifted in the other 5 direction moving said rollers toward each other, and a sprinkler adjustably held over said rollers.

In testimony whereof I affix my signature in the presence of two witnesses.

HERMAN J. FREDERICK.
